UNITED STATES PATENT OFFICE.

ASHELEIGH S. MOSES, OF ST. LOUIS, MISSOURI, ASSIGNOR TO NATIONAL LEAD COMPANY, OF ST. LOUIS, MISSOURI, A CORPORATION OF NEW JERSEY.

INKING MECHANISM FOR ROTARY MULTICOLOR-PRINTING PRESSES.

1,187,442.

Specification of Letters Patent. Patented June 13, 1916.

Original application filed March 12, 1913, Serial No. 753,750. Divided and this application filed August 29, 1913. Serial No. 787,359.

To all whom it may concern:

Be it known that I, ASHELEIGH S. Moses, a citizen of the United States, and residing at St. Louis, in the State of Missouri, have 5 invented certain new and useful Improvements in Inking Mechanisms for Rotary Multicolor-Printing Presses, of which the following is a specification.

This invention relates to multi-color printing presses and more particularly to printing presses adapted to print in different colors on cylindrical articles such as buckets and the like.

This application is a division of application Serial No. 753,750, filed March 12, 1913.

One of the objects of this invention is to construct inking mechanism which is adapted to apply ink of different colors to the printing mechanism.

20 Another object is to provide novel inking mechanism which is simple in construction, capable of adjustment, accessible, and which will distribute and apply the ink uniformly.

Further objects will appear from the detail description taken in connection with the accompanying drawings, in which:

Figure 1 is a plan of a machine embodying this invention, Fig. 2 is a front elevation, Fig. 3 is a partial side elevation, of 30 one of the printing cylinders and its ink supplying means, the view being taken looking in the direction of the arrow 3 Fig. 1, Fig. 4 is a section on the line 4—4 Fig. 1, Fig. 5 is a section on the line 5—5 Fig. 1, Fig. 6 is a detail section on the line 6—6 Fig. 2, Fig. 7 is a section on the line 7—7 Fig. 3, Fig. 8 is a partial section on the line 8 Fig. 3, Fig. 9 is a section on the line 9—9 Figs. 2 and 6, and Fig. 10 is a front elevation of a bucket.

Referring now to the accompanying drawings 10 designates a base plate for supporting the bearings, brackets, etc. A main drive shaft 11 is supported in bearings 12 and 13 on the base plate and projects beyond the same. A platen or mandrel 14 is mounted upon and keyed to the projecting end of the shaft and this mandrel is of tapered construction as shown. A sleeve 15 surrounds the shaft 11 and this sleeve has keyed thereto a driving pulley 16. The driving pulley 16 and the drive shaft 11 are arranged to be connected by means of a clutch generally indicated at 18 and having

a treadle operated clutch shifting rod 19. 55 This clutch may be of any suitable construction but is preferably of the single revolution type, that is, so constructed that the shaft will upon depression of the treadle make a single revolution and then come to 60 a stop in a predetermined position. Clutches of this type are however well known commercial devices and a detail description is therefore unnecessary.

A pair of shafts 20 are mounted in brackets 21 and 22 adjustably mounted on the base plate by means of screws 23 passing through slots in the brackets and tapped into the base plate. Adjusting screws 24 mounted in lugs 25 on the base plate and 65 engaging the brackets are provided for adjusting the brackets and the shafts laterally on the base plate. Each of the shafts 20 is provided with a reduced portion 26 adapted to receive a printing cylinder 27 of 70 segmental form which is clamped in position on the shaft by means of a nut 28. Each of these cylinders is provided with a printing surface or form 29 of rubber or other suitable material and having printing 75 characters thereon. The shafts 20 are driven from the main drive shaft 11 by means of gears 30 keyed to the shafts 20 and meshing with a gear 31 keyed to the shaft 11. Where the mandrel is of tapered 80 construction the gears 30 and 31 are bevel gears. In order to brake the machine each of the shafts 20 is provided with a friction drum 32 engaged by a friction brake 33. The base plate supports a pair of heads 40 85 which overhang the printing cylinders. These heads support the inking mechanisms hereinafter described.

The inking mechanism will now be described, and since the inking mechanisms for 90 the two printing cylinders are identical only one will be described in detail. The printing head 40 has an overhanging part, which is provided with a pair of side members 41 forming bearings for the inking rolls. A 100 pair of composition form inking rolls 42 are adjustably mounted in the side members and retained in position therein as follows: The shafts of these rolls are mounted in U shaped blocks 43 movable vertically on the 105 side members and having cheeks or lugs 44 bearing against the side members as shown in Fig. 9. Each of these blocks has a dove-

tailed slot 45 engaged by the head of a screw 46 threaded into a lug 47 projecting from the side member and having the end thereon slotted so that it can be engaged by 5 a screw driver or other suitable tool. By means of this construction the blocks 43 can be adjusted vertically on the side members to adjust the rolls 42 toward and from the printing cylinders. The rolls and blocks 10 are retained in position by means of latches 48 pivoted on screws 49 tapped into the lugs 47 and having lugs 50 thereon adapted to engage the ends of the shafts of the rolls 42. When the latches are thrown up out of 15 latching position the inking rolls can be readily removed, while when these latches are in position as shown in Figs. 2 and 3 they retain the rolls in position and against removal at the same time permitting adjustment 20 of the blocks 43 and the rolls carried thereby. The connection between the blocks and the screws 46 permits these blocks to be removed and replaced. The lug 50 when in position engages the side of the block 43 while the latch body engages the front of 25 the block to retain it in position. After the latch is in position it may be clamped by its screw 49.

A pair of plates 51 are secured to the side 30 members 41 by means of screws 52 and these plates support the shaft 53 of a brass distributing roll 54. The shaft 53 carries a cam head 55 sliding and rotating in a bearing bracket 56 and having a cam groove 57 engaged by the end of the pin 58 threaded into the bracket. The shafts 53 have each a pulley 59 driven by belts 60 from a pulley 61 keyed to the sleeve 15. Guide pulleys 62 are also provided for the belts 60 to sustain 35 them laterally. By means of this construction the shafts 53 are rotated and given an endwise movement while rotating, and in view of the fact that these shafts are driven from the continuously rotating sleeve 15, the distributing rolls 54 are continuously rotated and reciprocated laterally.

A composition ink-receiving roll 63 mounted in stirrups 64 on the side members 41 engages with the distributing roll 54. 50 A brass supply roll 65 is mounted between side members 66 pivoted at 67 on a block 68 mounted on the head 40. The block 68 is formed and beveled as shown at 69 so as to form with the side members 66 and the roll 65 an ink fountain. The shaft 70 of the roll 65 is driven intermittently by an intermittent clutch comprising a cylindrical casing 71 secured to the shaft, a head 72 mounted in and movable in the casing and attached 55 to an arm 72, and balls or rolls 73 between the casing and head. The arm 72 is oscillated through a link 74 from a bell crank lever 75 loosely mounted on a shaft 76 supported in bearing lugs 77 on the head 40. 60 By means of this construction oscillation of

the bell crank lever 75 will cause an intermittent movement of the roll 65 in the direction of the arrow Fig. 7. In order to regulate the space between the block 68 and the roll 65, so as to regulate the feed of the ink, the side members 66 are arranged for movement on their pivot 67, and these side members are adjusted by means of screws 78 extending loosely through the side members 66 and threaded into the head 40. The 75 springs 79 hold the roll in adjusted position. A composition transfer roll 80 is removably mounted in the ends of arms 81 rigidly connected to the shaft 76. The bell crank lever 75 is yieldingly connected to the 80 shaft 76 by means of a coil spring 82 on the shaft connected at one end to a collar 83 on the shaft and at its other end to a boss 84 on the bell crank lever. By means of this construction the shaft 76 will be actuated yielding 85 in both directions. The bell crank levers 75 are operated through a cross head 85 mounted on a slide 86 moving in a guide-way 87 and having a cam roll 88 engaging a cam 89 keyed to the shaft 11. The cross 90 head is returned by a spring 90.

During the upward movement of the cross head the transfer roll 80 will be thrown into contact with the receiving roll 63 and since this roll 63 is continuously driven by the roll 54 the ink will be taken off of the roll 80 and transferred to the roll 63. During the return or downward movement of the cross head and when the parts are moving in the direction of the arrows Figs. 5 95 and 7 the transfer roll 80 will be thrown into engagement with the supply roll 65, and since the movement takes place through the spring 82 the engagement between the rolls 80 and 65 will be a yielding one. During 100 the return or downward movement of the cross head the arm 72 and the clutch connection between this arm and the roll 65 will cause this roll to be moved in the direction of the arrow Fig. 7 to present the inked portion 105 of the roll to the transfer roll 80. The transfer roll 80 moves into engagement with the supply roll 65 while the latter is rotating, and in view of the fact that the yielding connection between the bell crank 75 and the shaft 76 causes the rolls 80 and 65 to be 110 in engagement for some time while the roll 65 is still moving in the direction of the arrow Fig. 7, the ink will be transferred from the roll 65 to the roll 80.

During the operation of the machine, as 115 fully described in the original application referred to, the supply roll 65 will transfer the ink to the transfer roll 80, the latter will in turn transfer the ink to the continuously rotating and endwise moving distributing roll 54 through the roll 63, and the distributing roll will supply and distribute the ink uniformly on the inking rolls 42. The inking rolls apply 120

the ink to the printing cylinders as they rotate thereunder. It will be understood that the fountains of the two printing mechanisms are supplied with different colored inks, so as to apply ink of one color to one printing cylinder and ink of another color to the other printing cylinder.

Fig. 10 shows a printed bucket. The letters have a body of one color and a border of another color. In the operation of the machine, as described in the original application referred to, the body of these letters will be printed by one printing cylinder while the border will be printed by the other printing cylinder.

It is obvious that various changes may be made in the details of construction without departing from the spirit of this invention and it is therefore to be understood that this invention is not to be limited to the specific construction shown and described.

Having thus described the invention what is claimed is:

1. In a printing press, inking mechanism comprising a support, a roll, a block carrying said roll, and a device detachably connected to the block and adapted to suspend the latter adjustably from said support, the connection between said device and block being constructed to permit lateral removal of said block with said roll from said support.

2. In a printing press, inking mechanism comprising a support, a roll, a block carrying said roll and provided with a dovetailed slot, and a screw having its head fitted in said slot and arranged to suspend said block adjustably from said support while permitting removal of the block laterally away from the support.

3. In a printing press, inking mechanism comprising a support, a roll, a block carrying said roll, means for mounting said block for vertical and lateral movements on said support, and means for adjusting said block vertically, constructed to permit lateral removal of said block and said roll from said support.

4. In a printing press, inking mechanism comprising a support, a roll, a block carrying said roll, means for mounting said block for vertical and lateral movements on said support, means for adjusting said block vertically, constructed to permit lat-

eral removal of said block and said roll from said support, and a latch for retaining said block in operative position.

5. In a printing press, inking mechanism comprising a support, a roll having a shaft and removably arranged on said support, and latches mounted on said support for movement parallel to said shaft and having lugs adapted to engage said shaft and retain said roll in position.

6. In a printing press, inking mechanism comprising a support, a roll, blocks for said roll arranged on said support, for vertical adjustment thereon and transverse removal therefrom, and latches on said support adapted to engage and retain said blocks in position.

7. In a printing press, inking mechanism comprising a support, a roll having a shaft, blocks having recesses for removably supporting said shaft, said blocks being removably arranged on said support, and latches mounted on said support and acting to retain said blocks in place, said latches having lugs adapted to engage said shaft and hold the same in said recesses.

8. In a printing press, inking mechanism comprising a beveled block, a pair of arms mounted on opposite sides of and engaging said block, and a roll carried by said arms and arranged adjacent said block, said parts forming together an ink fountain.

9. In a printing press, inking mechanism comprising a block, a pair of arms mounted on opposite sides of and engaging said block, a roll carried by said arms and arranged adjacent said block, said parts forming together an ink fountain, and means for adjusting said arms and said roll with respect to said block.

10. In a printing press, inking mechanism comprising a block, a pair of arms mounted on opposite sides of and engaging said block, a roll carried by said arms and arranged adjacent said block, said parts forming together an ink fountain, means for adjusting said arms and roll with respect to said block, and means for rotating said roll.

In testimony whereof I affix my signature in the presence of two witnesses.

ASHELEIGH S. MOSES.

Witnesses:

C. M. SHIRLEY,
JAS. L. PLATT.
